UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,942, dated June 24, 1890.

Application filed April 15, 1890. Serial No. 348,104. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the vertical or body part, and extends upwardly and supports the cross-bar B, which 15 is of plain surface and with oblique plain ends C C. The upper part of the body, where it encircles the cross-bar B, is formed with vertical ribs D, which, as they descend upon either side, spread laterally, forming the lower 20 ornamental ribbed portion H. Immediately

upon each side of the ribbed portion D the cross-bar B is relieved by two annular rings E E, highly ornamented. The body part A is bounded on the bottom by a base part G, which is ornamented, and that portion of the 25 body between the said part G and the part H is slightly swelled and shaded to act as a relief to the plain portions H D.

The handle is made of any suitable material.

Having now described my new design, what 30 I claim as new, and desire to secure by Letters Patent, is—

The design for umbrella or cane handles, substantially as herein described and shown.

In testimony of which invention I have 35 hereunto set my hand.

HENRY O. SCHMIDT.
